(74) Attorney, Agent, or Firm—Birch, Stewart, Kolasch & Birch, LLP.

(57) **CLAIM**

The ornamental design for a data input and cursor control device, as shown and described.

DESCRIPTION

FIG. 1 is a right side elevational view of a data input and cursor control device showing my new design;
 FIG. 2 is a left side elevational view thereof;
 FIG. 3 is a front elevational view thereof;
 FIG. 4 is a rear elevational view thereof;
 FIG. 5 is a top plan view thereof;
 FIG. 6 is a bottom view thereof;
 FIG. 7 is a right side elevational view of a data input and cursor control device showing my new design;
 FIG. 8 is a left side elevational view thereof;
 FIG. 9 is a front elevational view thereof;
 FIG. 10 is a rear elevational view thereof;
 FIG. 11 is a top plan view thereof; and,
 FIG. 12 is a bottom view thereof.
